UNITED STATES PATENT OFFICE

2,551,007

MASTHEAD

Frank Jones, McPherson, Kans.

Application December 21, 1948, Serial No. 66,438

3 Claims. (Cl. 254—139)

1

This invention relates to a masthead for portable hoisting apparatus used in servicing oil wells, and has particular reference to a masthead of the type wherein an upper pulley is mounted on an axis disposed transversely of the axis of a lower pulley.

Heretofore mastheads of the above type have been built so that the upper pulley is situated off to the front side of the mast, thereby imposing a bending strain on and inducing swaying of the mast when handling heavy loads. This creates a distinct hazard to the ground crew because continued bending and swaying of the mast causes the same to crystallize and break off near the masthead.

The primary object of the present invention is to provide a satisfactory masthead in which the upper pulley is mounted directly over the lower pulley and in line with the mast, thereby substantially eliminating bending stress on the mast, reducing its tendency to sway, and increasing its load capacity.

The exact nature of the present invention, as well as other objects and features thereof, will become apparent from the following description when considered in connection with the accompanying drawing, in which:

Figure 1 is a fragmentary perspective view showing a masthead made in accordance with the present invention mounted upon a mast and having a hoist line and a pulley block operatively associated therewith.

Figure 2 is an enlarged rear elevational view thereof with the hoist line and pulley block omitted.

Figure 3 is a side elevational view of the construction shown in Figure 2.

Referring in detail to the drawing, 5 indicates a tubular mast having the present masthead mounted on the upper end portion thereof. The masthead includes a pair of similar brackets 6 having their lower portions welded or otherwise rigidly secured to opposite sides of the upper end portion of mast 5 and disposed in spaced parallel relation. The upper portion of each bracket 6 is longitudinally slotted to provide a pair of spaced upwardly projecting arms 7 and 8, the slot 9 being disposed at a slight rearward angle to the mast. Corresponding arms of the brackets are connected by bolts 10 and 11, the bolts 10 extending through spacer sleeves 12. The lower portions of the brackets are provided on their outer sides with spaced longitudinal reinforcing ribs 13, and disposed between and secured to these ribs at the lower portions of the slots 9

2

are aligned hanger blocks 14 in which are secured, by bolts 15 or the like, the ends of a transverse axle 16. A lower pulley 17 is journaled on the axle 16 between the brackets and guard ribs 18 are provided on the inner faces of the brackets concentric with axle 16 to prevent the hoist line L from jamming between the brackets and pulley in case said hoist line should ride off of the latter.

Hanger blocks 19 are respectively secured by 10 the bolts 11 between the upper ends of arms 7 and arms 8, and the ends of an axle 20 are secured in said hanger blocks by said bolts. An upper pulley 21 is journaled on the axle 20 and projects through the upper portions of slots 9 and above 15 the arms 7 and 8. Guard brackets 22 are disposed at opposite sides of the upper portion of pulley 21 and have central depending shanks 23 which are outwardly offset and secured to the outer sides of hanger blocks 19 by bolts 24. The 20 ends of guard brackets 22 are connected by bolts 25 extending through spacer sleeves 26, and ribs 27 are provided on the inner faces of these brackets at the top of pulley 21 to prevent the hoist line from jamming between said pulley and 25 guard brackets in case said line should ride off of the pulley. It will be noted that the upper pulley 21 is located directly over the lower pulley 17 substantially in line with the mast, and that it is slanted at a slight rearward angle to the mast. A pulley block 28 is suspended by the hoist line 30 in front of the mast, said hoist line passing over the lower pulley 17 to and through the pulley block, then over the upper pulley 21, and finally being attached at 29 to the pulley block.

The present mast is simple, compact and durable in construction, and the upper pulley is so located and arranged as to substantially eliminate bending stress on the mast and to permit raising of the pulley blocks substantially to the top of the mast. Modifications and changes in details 40 of construction are contemplated, such as fairly fall within the spirit and scope of the invention as claimed.

What is claimed as new is:

1. In a hoist, a mast, a support mounted on the upper end of said mast, an axle carried by said support transversely of and in line with the mast, a second axle carried by said support and disposed higher than and transverse to the first-named 45 axle and transversely of and in line with the mast, a pulley on each of said axles, the pulley of the second-named axle being disposed directly over the first-named axle and at a slight rearward angle to the mast, said support comprising a pair 50 of similar brackets rigidly secured to opposite

sides of the mast and disposed in spaced parallel relation, each bracket having a longitudinal slot receiving and extending upwardly from the first-named axle and disposed at a slight rearward angle to the mast, each slot defining a pair of spaced arms, and hanger blocks for the second-named axle secured between corresponding arms of the brackets, the pulley on said second-named axle projecting through said slots and above the arms.

2. The combination of claim 1 and guard brackets secured to said hanger blocks and disposed at opposite sides of the upper portion of the last-named pulley and extending to the top of said last-named pulley.

3. In a hoist, a mast, a support mounted on the upper end of said mast, an axle carried by said support transversely of and in line with the mast, a second axle carried by said support and disposed higher than and transverse to the first-named axle and transversely of and in line with the mast, a pulley on each of said axles, the pulley on the second-named axle being disposed directly over the first-named axle and at a slight rearward angle to the mast, said support comprising

a pair of similar brackets rigidly secured to opposite sides of the mast and disposed in spaced parallel relation, each bracket having a longitudinal slot receiving and extending upwardly from the first-named axle and disposed at a slight rearward angle to the mast, each slot defining a pair of spaced arms, hanger blocks for the second-named axle secured between corresponding arms of the brackets, the pulley on said second-named axle projecting through said slots and above the arms, guard brackets extending to the top of said last-named pulley, spaced longitudinal ribs on the outside of said brackets, and further hanger blocks for the first-named axle secured between 15 said ribs at the lower portions of said slots.

FRANK JONES.
